CLAIM

The ornamental design for a wall or post mounted bag dispenser, as shown and described.

DESCRIPTION

FIG. 1 is a front, top and side-perspective view of a wall or post mounted bag dispenser embodying my new design, wherein an exemplary post is illustrated in phantom in forms no part of the design;

FIG. 2 is a top, rear and side-perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
